UNITED STATES PATENT OFFICE.

ISIDOR SIMOVITZ, OF NEW YORK, N. Y.

FLUSHING DEVICE.

1,287,476.

Specification of Letters Patent. Patented Dec. 10, 1918.

Application filed June 13, 1918. Serial No. 239,789.

To all whom it may concern:

Be it known that I, ISIDOR SIMOVITZ, a citizen of the United States, and a resident of the city of New York, borough of Bronx, in the county of Bronx and State of New York, have invented a new and Improved Flushing Device, of which the following is a full, clear, and exact description.

This invention relates to flushing devices for toilets and for other purposes, and has for an object the provision of an improved construction wherein the ordinary flush valve is eliminated and a siphon is substituted.

Another object in view is the provision of a flushing device provided with an ordinary valve structure and means for automatically shutting the same off when the tank has been filled, and a siphon positioned to be operated as soon as the valve has been opened.

A still further object of the invention is to provide a flushing device with an ordinary inlet valve and an arrangement of operating mechanism which will comparatively disconnect the float from the valve until the tank has been emptied.

In the accompanying drawings:

Figure 1 is a longitudinal vertical section through part of a tank and flushing device disclosing an embodiment of the invention.

Fig. 2 is a top plan view of the structure shown in Fig. 1.

Fig. 3 is a view similar to Fig. 1, but showing the parts in the position assumed when the operating cord has been pulled.

Fig. 4 is a view similar to Fig. 3, but showing the parts in the position assumed when the tank has been emptied.

Referring to the accompanying drawings by numerals 1 indicates a tank of any desired kind provided with an opening having a fitting 2 of any usual preferred construction, said fitting being designed to receive the lower end of the siphon 3, which lower end may be held in place by being beveled and forced tightly in position in connection with some packing 4, or may be held in position by having the parts threaded and screwed into place. The siphon 3 may be made of any suitable material and substantially in any desired way, but arranged with an up-passageway 5, a trans-

verse-passageway 6 and a down-passageway 7 merging into an outlet. The up-passageway 5 is provided with an opening 8 and one or more apertures 9 slightly above the opening 8 so as to break the siphon when the tank is substantially emptied. It will be noted that by using the siphon 3 no outlet valve is necessary and the water is maintained properly in tank 1 either with the water line level with the top of the wall 10 or slightly below said top. An inlet valve 11 of usual construction is provided having a plunger 12 formed with an opening 13 into which the arm 14 projects. A set screw 15 is provided in the end of the casing of valve 11 so as to limit the movement of the plunger 12 and arm 14 to any desired extent, as for instance to take up wear. The water from valve 11 passes through the discharge member 16 into the pipe 17 and from thence through the pipe 18 to a point near the opening 8. Preferably the end of pipe 18 is bent and also preferably slightly tapered so that the water will project directly into the opening 8 and from thence up the upleg or passageway 5 so as to quickly start the action of the siphon. After the siphon 75 has been started in this manner, or by raising the water level in the tank it will continue to operate until the siphon is broken by air entering one of the openings 9. If pipes 17 and 18 were omitted the siphon 3 80 would operate but it would be necessary for the level of the water in the tank to move upward by water flowing through valve 11 into the tank. This would occupy a short time, as for instance a few seconds, and in 85 order to eliminate this slow response pipes 17 and 18 are utilized for causing a substantially instantaneous response when the operating cord 19 is pulled. When this cord is pulled lever 20 is moved on its pivotal support 21 which support extends through the lug 22 of the plate 23. In connection with plates 23 it will be observed that the same is provided with lugs 24 and 25 for accommodating certain screws or fastening means for clamping the valve 11 in position, plate 23 being screwed or otherwise rigidly secured to the tank 1. When the string or cord 19 is pulled lever 20 will be operated as just described and the chain 100 105 26 pulled so that the pawl or catch 27 will

be moved upwardly, as instance to the position shown in Fig. 3, said pawl being pivotally mounted at 28 on lever 29 rigidly secured to the arm 14. Arm 14 is mounted on the casing of valve 11 and is held in place by having a pivotal pin 30 pass through suitable lugs 31 extending from the casing of valve 11. A fitting 32 is pivotally mounted at 33 on the end of lever 29, said fitting having an upstanding lug 34 for engaging the end of the pawl 27 for holding the fitting 32 in alinement with the lever 29 as shown in Figs. 1 and 4. Fitting 32 carries the rod 35 which has secured to it the usual float 36. When the pawl 27 is in operative position as shown in Figs. 1 and 4 fitting 32 and rod 35 act merely as elongations of the lever 29 whereby the buoyancy of the float 36 will cause the reciprocating valve member 12 to press tightly against its seat and thereby shut off the flow of water from the supply pipe 37. It will be, of course, understood that the tank 1 will be full of water or at least supplied with water to the usual level when the pawl 27 is disengaged, the water being thus supplied when in the position shown in Fig. 1. The disengagement of the pawl 27 will cause the weight of the various parts and the water pressure on the valve member 12 to move the lever 29 and associate parts to substantially the position shown in Fig. 3. The downward movement of the various parts just described will cause the end of pawl 27 to engage the slanting side 38 of lug 34 instead of the straight face 39. This being the case the water will flow out of the siphon 3 until the tank has been emptied and consequently the various parts have been lowered to the position shown in Fig. 4, whereupon pawl 27 will move over the lug 34 so as to engage the flat surface 39 of lug 34 the ends of the plunger or valve member 12 limiting the movement of lever 29 so as to insure this action. When the parts assume the position as shown in Fig. 4 the siphon is broken, the water continues to enter the tank and as the tank becomes more and more filled pawl 36 will be moved upwardly until it again assumes the position shown in Fig. 1, whereupon the valve member or plunger 12 will be moved to the closed position for shutting off the water from supply pipe 37.

What I claim is:

1. In a flushing device of the character described, the combination of a tank, a siphon member arranged in said tank extending through the bottom thereof so that when it is in operation water will flow from the interior of the tank to the exterior until the tank is substantially empty, a supply valve, an inlet member for the tank, a lever structure formed in two parts for normally closing said valve, said lever having a float on the outer end, a catch for holding the two

parts of the lever structure in alinement normally, manually operated means for disconnecting said catch when it is desired to flush the tank whereby said valve is opened and maintained open until the float has been moved downwardly a predetermined distance to cause the catch to become interlocked again.

2. In a flushing device of the character described, the combination of a tank with a siphon member arranged in the tank, an inlet valve, a lever pivotally mounted on said inlet valve for normally acting to hold the same closed, an arm carrying a float pivotally mounted on the outer end of said lever, a stop projecting from said arm, a pivotally mounted catch arranged on said lever and adapted to engage said stop when the arm and the lever are in alinement for locking the same in alinement, and manually operated means for disconnecting said catch whereby the valve will open and remain open until the catch has been again closed and the tank refilled.

3. In a flushing device of the character described the combination of a tank having a discharge structure, an inlet valve for directing water into the tank, an arm pivotally mounted on said valve for actuating the valve plunger therein, an arm pivotally mounted at the outer end of said lever, said arm carrying a float, a stop projecting from said arm, a catch pivotally mounted on said lever formed with an engaging end adapted to engage one face of said stop for normally holding said lever and said arm in alinement, and means for disengaging said catch whereby the weight of the parts and the pressure of the water will cause the valve to open and thereby move the lever in such a position that the catch will engage the stop until the water has been discharged from the tank and the float caused to move down a predetermined distance.

4. In a flushing device of the character described, the combination with a tank of a discharge member for said tank, a valve inlet member for the tank, a jointed controlling structure for normally holding the valve member against its seat, a catch for maintaining said jointed structure normally in alinement, a float arranged on the end of said jointed structure, and means for manually disengaging said catch so that only part of the jointed structure will move pivotally a predetermined distance and thereby prevent said catch from again engaging the structure until the tank has been substantially emptied.

5. In a flushing device of the character described, the combination with a tank and a discharge member of a supply valve, a lever structure formed in two parts for normally closing said valve, said lever having a float on the outer end, a catch for holding

the two parts of the lever structure in alignment normally, manually operated means for disconnecting said catch when it is desired to flush the tank whereby the valve is 5 opened and moved down until the float has been moved downwardly a predetermined distance to cause the catch to become again

interlocked, and means for limiting the swinging movement of that part of the lever contacting with the valve so that the part 10 of the lever carrying the float may come in alignment before the float strikes the bottom of the tank.
